(57) **CLAIM**

The ornamental design for a multinational travel conversion socket, as shown and described.

DESCRIPTION

FIG. 1 is a perspective view of a multinational travel conversion socket showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an exploded view of the socket in a second state;

FIG. 10 is a perspective view of the socket in a third state;

FIG. 11 is a perspective view of the socket in a fourth state;

FIG. 12 is a perspective view of the socket in a fifth state; and,

FIG. 13 is a perspective view of the socket in a sixth state. In the drawings, the broken lines are for the purpose of illustrating environment only and form no part of the claimed design.
